BUS TRANSFER SYSTEM

Earl B. Ankenman, Braintree, Mass., assignor to
Westinghouse Electric Corporation, East Pitts-
burgh, Pa., a corporation of Pennsylvania

Application February 28, 1947, Serial No. 731,510

9 Claims. (Cl. 318—393)

1

My invention relates to bus transfer systems for variable-voltage direct-current motors. In such systems, the motor to be accelerated to the desired operating speed is first energized from starting connections whose voltage is gradually raised to the value required for the desired motor speed, and the accelerated motor is then transferred to the running connections to which the motor remains attached during its further performance. Systems of this kind are in use for sectional fabricating machinery, such as sectional paper machines, which have several motors operated from a variable-voltage generator and whose sections must permit being started independently of other sections that may be running at the time of the start.

The known bus transfer systems of the kind mentioned are controlled by an electromagnetic voltage-responsive relay whose contacts initiate the switching operation when the voltage difference between the running bus and the starting bus becomes sufficiently low. The transfer performance of such a voltage relay is sometimes unsatisfactory or rough because the electromagnetic relay may change its pick-up point due to changes in temperature, and it may happen that the motor, though under the proper voltage, has as yet not sufficiently accelerated for a smooth transfer.

It is an object of my invention to provide bus transfer systems that secure automatically a smooth transfer at any time. More in particular, my invention aims at devising a transfer system whose transfer conditions are not affected by those changes in temperature or other ambient conditions that are apt to disturb the proper performance of the electromagnetic voltage relays heretofore used for initiating the switching operation. Another more specific object of my invention is to permit and initiate a bus transfer only when the voltage differential between starting and running buses is sufficiently low or zero and when, in addition, the motor has ceased accelerating.

These and other objects of the invention as well as the means provided by the invention for achieving them will be apparent from the following description of the embodiments illustrated in the drawings, in which:

Figure 1 represents the circuit diagram of a sectional drive appertaining to a paper machine and designed in accordance with the invention, while Fig. 2 is a similar circuit diagram of another embodiment also representing a sectional paper machine drive.

2

According to Fig. 1, the machinery to be driven comprises a number of sections, such as those denoted by S1 and S2, with appertaining direct-current motors M1 and M2 which can be started and operated independently of each other and independently of any other sectional drive but which during their operation must maintain a given speed or positional relation to one another. As illustrated, the machine section S1 consists of 10 a roll press from which the material 1 passes over guide rollers 2, 3 and 4 through the section S2, here represented as a calender.

The armature 5 of drive motor M1 has one of its poles permanently connected to a common negative bus 6 of a running generator GR and a starting generator GS. The other pole of the motor armature 5 is selectively connectible to the positive bus 7 of the starting generator GS and to the positive bus 8 of the running generator GR. 15 The selective connection is effected by means of two mutually interlocked contactors C1 and C2 under control by two electromagnetic relays R1 and R2 in conjunction with an electronic tube circuit and other circuit devices to be described in a later place. The contactors C1, C2 and the appertaining other control devices represent together a control system which is denoted as a whole by CS1.

The field winding 9 of drive motor M1 is connected to a suitable source 10 of constant direct-current voltage through a rheostat 11. The armature 12 of the drive motor M2 has its negative pole connected to the common generator bus 6 while its positive pole is connected to the starting bus 7 or the running bus 8 under control by a control system CS2 which contains contactors and relays designed and operative in the same manner as those of the control systems CS1 and hence not illustrated in detail. The field winding 13 of motor M2 is energized from a constant voltage source 14 through an adjusting rheostat 15. While the voltage sources 10 and 14 are schematically represented as separate units, they may, of course, consist of one and the same device which may be identical with the direct-current source described hereinafter as supplying energization for the direct-current elements of the control system CS1.

50 The contactor C2 has a contact 17 which, when closed, connects the motor M1 to the running bus 8. The contact member 17 is controlled by a coil 18 which actuates also an interlock contact 19. The contactor C1 has a main contact 21 55 which, when closed, connects the motor M1 to

the starting bus 7. The control coil 22 of contactor C1 actuates also an interlock contact 28 in the coil circuit of contactor C2. The interlock contact 19 of contactor C2 is series connected in the circuit of coil 22. Due to these interlock connections, only one of contactors C1 and C2 can be closed at a time. The motor circuit controlled by contact 21 includes a series rheostat 24 so that the voltage drop across this rheostat is a measure of the current drawn by the motor armature 5 when the motor M1 is energized from the starting bus 7.

The excitation for the contactor coils 18 and 22 is derived from the terminals 25 and 26 of a direct-current source which, as mentioned above, may be identical with the source of field excitation for motors M1 and M2. The coil circuit of contactor C2 includes in series a normally open contact 27 of a control relay R1, while the coil circuit of contactor C1 includes in series a normally closed contact 28 of the same relay R1. Both contacts 27 and 28 are under control by the relay coil 29. The circuit of contactor coil 22 extends further through a control contact 30 to be actuated by the operator for starting the motor M1.

The relay coil 29 receives excitation from the terminals 25 and 26 under control by an electronic discharge tube 31, for instance, of the thyratron type. The plate circuit of this tube, extending through the coil 29, includes also a control contact 3 appertaining to a voltage relay R2 whose control coil 33 actuates also two additional contacts 34 and 35.

The tube 31 serves a trigger device. Its control grid 36 is connected through a resistor 37 and the above-mentioned contact 34 to the tap point P1 of the current measuring rheostat 24 in the starting connections of the motor M1. A grid bias capacitor is denoted by 38. Connected between the starting bus 7 and the running bus 8 is a rheostat 39 which develops a voltage drop corresponding to the voltage difference between the running bus 8 and the starting bus 7. This connection is controlled by the above-mentioned contact 35 of the voltage relay R2 whose coil 33 is also connected across the buses 7 and 8. The grid circuit of tube 31 can be traced from grid 36 through resistor 37, contact 34, point P1 of rheostat 24, point P2, rheostat 39, point P3, and contact 40 to the cathode of tube 31. It will be noted that this grid circuit contains two sources of control voltage, one being represented by the tapped portion P1—P2 of rheostat 24 and the other by the tapped portion P2—P3 of the rheostat 39. The voltage imposed on the grid circuit along the rheostat portion P1—P2 is proportional to the current of the motor M1, while the voltage imposed on the grid circuit along the rheostat portion P2—P3 is proportional to the voltage differential between the starting and running buses 7 and 8. This grid circuit, however, is closed only when the voltage relay R2 is in the illustrated dropped-off condition and when the contactor C1 is energized to attach the motor M1 to the starting connections.

The armatures of the generators GR and GS are denoted by 41 and 42, respectively. The field winding 43 of the running generator is excited from a source 44 of constant voltage through a controlling rheostat 45. The field winding 46 of the starting generator GS receives excitation from a voltage source 47 through a control rheostat 48. The voltage sources 44 and 47, here separately illustrated, may be associated with the above-

mentioned other sources of direct-current voltage.

The rheostats 41 and 45 in the motor field circuits, once properly adjusted, need not as a rule be actuated during the normal performance of the system. Consequently, the speed of the motors M1 and M2 is normally determined by the voltage of the running generator GR or of the starting generator GS, and these voltages are adjustable by the respective rheostats 45 and 48. The rheostat 45 of the running generator GR is normally maintained at a setting which corresponds to the desired operating speed of the sectional fabricating machinery. The coil circuit of the voltage relay R2 is so rated that the relay R2 picks up when the voltage of the starting generator GS is below a given value which is lower than the voltage of the running generator GR within the normal voltage or speed range of the system. The tube 31 has its circuits so rated that a trigger effect occurs when the voltages of the starting bus 7 and running bus 8 are nearly equal, but the triggering is also dependent upon the disappearance of accelerating current in the motor circuit as will be understood from the description of an operating performance following presently.

For the purpose of explanation, it is assumed that the motor M2 and, possibly other motors of the sectional machinery, are attached to the running connections, i. e., between buses 6 and 8, and hence operate at the proper speed as determined by the setting of the rheostat 45. The motor M1 is assumed to be at rest and in condition to be started. For starting, the operator closes the contact 30. This completes the circuit of coil 22. Contactor C1 picks up and connects the motor armature 5 at contact 21 to the starting bus 7. The operator now starts the generator GS or if the generator was running, applies an increased field excitation thereto by progressively adjusting the rheostat 48. At the moment when contact 30 is closed, the full running voltage is effective across buses 7 and 8. Consequently, the voltage relay R2 picks up, opens the plate circuit of tube 31, and interrupts the appertaining grid circuit. As the starting voltage increases and causes the motor M1 to accelerate, a point will be reached where the voltage drop between buses 7 and 8 becomes insufficient to energize the coil 33 for a continued opening of the relay R2. As a result, the relay R2 drops out and prepares the tube circuits for the subsequent triggering and switching performance. As soon as this occurs, two cumulative blocking voltages are imposed on the grid circuit. These two voltages, as explained above, correspond to the declining voltage differential between buses 7 and 8 and to the declining current flowing through the starting connections of motor M1. Thereafter, as soon as the voltage differential between buses 7 and 8 become zero or drops below a given small value, the blocking voltage between points P2 and P3 of rheostat 39 disappears. This causes the tube 31 to be triggered unless at that moment the motor M1 is still accelerating. The accelerating current, causing a corresponding voltage drop between points P1 and P2 of rheostat 24, maintains the tube under cut-off bias, but when the motor M1 has reached the proper speed, this cut-off bias is also eliminated and the tube will then start conducting. As a result, coil 29 of relay R1 becomes energized and interrupts the coil circuit of contactor C1, while closing the contact 27 of the coil circuit of contactor C2. Contactor C1 interrupts

the starting connections, and contactor C2 establishes the permanent running connections for motor M1. The starting generator GS can then be stopped or its voltage can be reduced to zero, so that this generator is thereafter available for starting other machine sections. Motor M1 will continue running at the speed determined by the selected field excitation of generator GR until the current supplied from this generator ceases or until contactor PC is opened by the operator or by protective control devices.

It will be recognized from the foregoing that the bus transfer is controlled by the tube 31 and hence is virtually not affected by changes in ambient temperature or other conditions. This transfer is further jointly dependent on the simultaneous existence of two conditions, namely, the disappearance or given decrease in the voltage differential between starting and running buses and on the disappearance or given decrease of accelerating current in the motor to be started. Thus a smooth transfer is secured under any condition of operation. To be sure, the voltage point of response of the relay R2 may be subjected to the same changes that occur in the electromagnetic control relay of the known transfer systems. However, in the above-described embodiment of my invention, the relay R2 does not control the bus transfer but serves merely as an auxiliary device which secures an increased life of the electronic device by switching the latter into the circuit only when the operating conditions of the system are close to a status where the more accurate control effect of the tube circuit is to be utilized. In other words, the rating of the coil circuit in relay R2 is such that the drop-out voltage is always below the voltage range in which tube is to be effective. Hence a change in the relay calibration does not affect the control performance proper. It should also be understood that if desired, the relay R2 can be eliminated or that it may be replaced by another electronic discharge device, for instance, in the manner shown in the embodiment of Fig. 2 and described hereinafter.

According to Fig. 2, a fabricating machinery with independently operable sections S3 and S4 is driven by respective motors M3 and M4 which are energized from the common negative bus 6, the starting bus 7 and the running bus 8 of a variable voltage system energized from a starting generator GS and a running generator GR in the same manner as described more in detail above with reference to Fig. 1.

The bus transfer performance for motor M3 in Fig. 2 is controlled by a control system CS3, and the corresponding bus transfer for motor M4 is under control by a similar system CS4, the latter not being shown in detail.

The control system CS3 includes two mutually interlocked contactors C3 and C4. The main contact 51 in contactor C3 is controlled by a coil 52, together with an interlock contact 53, and serves to connect the motor M3 across the buses 6 and 7 in series with a current measuring rheostat 54. The main contact 55 of contactor C4 is controlled by a coil 56 which actuates also four additional contacts denoted by 57, 58, 59 and 60, respectively.

A rheostat 61 is connected across the starting and running buses 7 and 8 and has a tap point P4 connected to the grid 62 of an electronic tube 63. The grid circuit includes a grid resistor 64 and a source 65 for applying a constant cut-off bias. The plate circuit of tube 63 is energized

through a transformer 66 by alternating-current and energizes a rectifier 67 through an output transformer 68. A rheostat 69 is connected across the output terminals of the rectifier 67 in parallel to a smoothing capacitor.

The current-measuring voltage drop across the tapped portion P4—P5 of rheostat 54 and the voltage drop occurring across the tapped portion of rheostat 69 when the tube 63 is conductive are cumulatively imposed on the grid circuit of a tube 70 preferably of the thyratron type. The grid circuit of tube 70 can be traced from grid 71 to a resistor 72, a source 73 of a constant bias voltage, the tap portion of rheostat 54, contact 60, and the tapped portion of rheostat 69 to the cathode of tube 70. The plate circuit of tube 70 includes the coil 74 of a control relay R2 and is energized from direct-current terminals 75 and 76 under control by the contact 57 of the contactor C4. The system includes further an operator-actuable switch whose two contacts 78 and 79 are to be closed by a push button or the like actuating member 80 in order to start the motor M1 and which has also a push button or the like member 81 to be actuated for stopping the motor M1. The performance of this system is as follows:

It is assumed in the following that the running generator GR is operating and that the motor M4 is running at the desired speed determined by the selected field excitation of generator GR. In order to start the motor M3, the actuating member 80 is depressed by the operator so that contacts 78 and 79 close. These contacts stay closed during the subsequent performance until the member 81 is actuated in order to stop the motor M3. The closing of contact 79 completes the circuit of coil 52 so that contactor C3 picks up and closes at contact 51 the starting connections for motor M1. At this moment the voltage of the generator GS is zero so that the voltage drop between points P5 and P6 of rheostat 61 corresponds to the full line voltage then effective. As a result, the normal blocking bias of source 45 65 is overcome and the tube 63 is triggered immediately or is raised to such a degree of conductance that a substantial voltage drop appears across the rheostat 69. This voltage drop imposes a negative cut-off bias on grid 71 of tube 50 70 which preponderates over the normal positive bias from source 73 and hence holds the tube 70 safely under non-conductive conditions. The starting generator GS is now caused to furnish an increasing starting voltage, so that the motor 55 M3 accelerates. The accelerating current causes a corresponding voltage drop to be effective across points P4 and P5 of rheostat 54, and this voltage drop has also the effect of overcoming the normal bias from source 73 in the grid circuit of tube 70. 60 As the voltage of the starting generator GS approaches the normal voltage range of the running generator GR, a point will be reached where the voltage drop across points P5 and P6 of rheostat 61 becomes insufficient to maintain the tube 63 sufficiently conductive. Then, the voltage drop across the tapped portion of rheostat 69 disappears or is reduced sufficiently to render the firing bias of source 73 effective. However, as long as the motor is still accelerating, the voltage drop across points P4 and P5 of rheostat 54 will still prevent the tube 70 from firing. With the motor M1 running at the properly matched speed, the conditions in the grid circuit of tube 70 are such as to trigger the tube. Then the relay R2 65 picks up and, by closing the contact 71, energizes

the coil 56 of contactor C4. Contact 55 closes and completes the permanent running connections for motor M1 while interlock contact 59 opens the coil circuit of contactor C3, so that the latter drops out. At that time, however, a self-holding circuit is closed for contactor C4 at contact 58. The contacts 57 and 60 interrupt the plate and grid circuits, respectively, of the tube 78 so that the performance of this tube is limited to a rather brief interval of operation. The subsequent actuation of button 81 has the effect of opening the contact 78 of the coil circuit for contactor C4 so that the latter will drop out and stop the motor M3. Thereafter the system is again in the initial condition illustrated in the drawings.

It will be understood by those skilled in the art that control systems according to the invention can be modified and altered in many respects, especially as regards the individual components of the control system and their mutual connections without departing from the above disclosed principles of my invention and within the scope of its essential features as set forth in the claims annexed thereto.

I claim as my invention:

1. A system for transferring a direct-current motor from starting to running connections, comprising voltage-responsive control means responsive to the occurrence of a given low differential voltage between running and starting connections, current-responsive control means responsive to the occurrence of a given low motor current, electromagnetic contactor means having contacts for switching the motor from starting to running connections and coil means for controlling said contacts, an electronic trigger tube having a plate circuit connected with said coil means and having a trigger circuit connected with said voltage-responsive control means and said current-responsive control means for triggering said tube only when both said control means have responded to said given voltage and current respectively.

2. A direct-current bus-transfer system, comprising a motor circuit, starting connections and running connections for energizing said motor circuit, electromagnetic contactor means disposed between said circuit and said connections and having coil means for switching said circuit from said starting connections to said running connections, a circuit member connected between said starting connections and said running connections to provide a first control voltage in accordance with the voltage difference of said respective connections, control means connected to said member so as to change its condition when said first control voltage drops below a given magnitude, another circuit member connected to said motor circuit for providing a second control voltage in accordance with the current in said motor circuit, an electronic trigger tube controlled by said control means and having a plate circuit connected to said coil means and a trigger circuit connected with said other member so as to be triggered only when said first control voltage is below said given value and said second control voltage is also below a given value.

3. A direct-current bus-transfer system, comprising a motor circuit, starting connections and running connections for energizing said motor circuit, electromagnetic contactor means for switching said motor circuit from said starting connections to said running connections, an electromagnetic relay having contacts connected to said contactor means for controlling the latter

5 and having a coil for actuating said contacts, an electronic tube plate-connected to said coil for providing energization for the latter, circuit means attached to said tube for controlling said energization and including two control means of which one is connected between said respective starting connections and running connections to respond to the differential voltage of said respective connections, while said other control means is connected to said motor circuit under control by said contactor means when said motor circuit is connected to said starting connections in order to respond to the current then flowing in said motor circuit so that said tube causes said relay to actuate said contactor means for switching said circuit from starting to running connections when said differential voltage and said current are both below given respective magnitudes.

4. A direct-current bus-transfer system, comprising a motor circuit, starting connections and running connections for energizing said motor circuit, electromagnetic contactor means for switching said motor circuit from said starting connections to said running connections, an electromagnetic relay having contacts connected to said contactor means for controlling the latter and having a coil for actuating said contacts, an electronic tube plate connected to said coil for providing energization for the latter and having a grid circuit for controlling said energization, two impedance devices connected in said grid circuit for impressing thereon two respective component control voltages, one of said impedance devices being connected between said starting connections and said running connections respectively as to furnish one of said control voltages in accordance with the voltage differential of said respective connections, said other impedance device being connected in said motor circuit to furnish said other control voltage in dependence upon the current flowing in said motor circuit when the latter is connected to said starting connections, said two impedance devices having a polarity of connection relative to each other in said grid circuit as is required to make said control voltages cumulative so that said tube causes said relay to effect switching of said motor circuit by said contactor means only when said voltage differential and said current are both below predetermined respective magnitudes.

5. A direct-current bus-transfer system, comprising a motor, a common bus connected to said motor, a starting bus and a running bus selectively connectable to said motor, a first electromagnetic contactor for connecting said motor to said starting bus, a second electromagnetic contactor for connecting said motor to said running bus, such of said contactors having a coil circuit controlled by the other contactor to provide a mutual interlock between said contactors, an electromagnetic relay having a normally closed first contact in said coil circuit of said first contactor and a normally open second contact in said coil circuit of said second contactor and having a coil for controlling said contacts, a control contact disposed in said coil circuit of said first contactor to permit closing said first contactor when said first contact is closed, an electronic tube having a plate circuit connected to said relay coil for causing it, when energized, to open said first contactor and closing said second contactor, and circuit means connected to said tube for controlling the latter and including two control means, one of said control means being connected across said respective starting and running buses to respond to the dif-

ferential voltage of said latter buses, and said other control means being connected to said motor to respond to the current flowing through said motor when said motor is connected to said starting bus, said two control means being disposed in said circuit means for conjoint control of said tube so that said tube causes said relay to respond only when said differential voltage and said current are both below predetermined respective magnitudes.

6. A direct-current bus-transfer system, comprising a motor, a common bus connected to said motor, a starting bus and a running bus selectively connectible to said motor, a first electromagnetic contactor for connecting said motor to said starting bus, a second electromagnetic contactor for connecting said motor to said running bus, each of said contactors having a coil circuit controlled by the other contactor to provide a mutual interlock between said contactors, an electromagnetic relay having a normally closed first contact in said coil circuit of said first contactor and a normally open second contact in said coil circuit of said second contactor and having a coil for controlling said contacts, a control contact disposed in said coil circuit of said first contactor to permit closing said first contactor when said first contact is closed, an electronic tube having a plate circuit connected to said relay coil for causing it, when energized, to open said first contactor and closing said second contactor, said tube having a grid circuit provided with two resistors, one of said resistors being connected between said starting bus and said running bus so as to impress on said grid circuit a component grid voltage proportional to the voltage difference of said latter buses, and said other resistor being connected to said motor so as to impress on said grid circuit another component grid voltage determined by the load current flowing through said motor, said two resistors being interconnected to make said two component grid voltages cumulative so that said tube causes said relay to switch said contactors only when said voltage differential and said current are below predetermined respective magnitudes.

7. In combination with a bus-transfer system as set forth in claim 6, an auxiliary electromagnetic relay having a coil connected across said starting bus and said running bus so as to be picked up when said voltage differential is high and being rated to drop out when said voltage differential drop below a given magnitude higher than the aforesaid predetermined magnitude, said auxiliary relay having a contact disposed in said plate circuit for interrupting the latter circuit when said auxiliary relay is in picked-up condition.

8. In combination with a bus-transfer system as set forth in claim 6, an auxiliary electromagnetic relay having a coil connected across said starting bus and said running bus so as to be

picked up when said voltage differential is high and being rated to drop out when said voltage differential drop below a given magnitude higher than the aforesaid predetermined magnitude, said auxiliary relay having a contact disposed in said plate circuit for interrupting the latter circuit when said auxiliary relay is in picked-up condition, another contact connected with said one resistor for opening its connection between said

10 starting bus and running bus as long as said auxiliary relay is in picked-up condition, and a third contact for disconnecting said grid circuit from said other resistor when said auxiliary relay is in picked-up condition.

15 9. A direct-current bus-transfer system, comprising a motor circuit, starting connections and running connections for energizing said motor circuit, electromagnetic contactor means for switching said motor circuit from said starting connections to said running connections, an electromagnetic relay having contacts connected to said contactor means for controlling the latter and having a coil for actuating said contacts, an electronic tube plate connected to said coil for providing energization for the latter and having a grid circuit for controlling said energization, two impedance devices connected in said grid circuit for impressing thereon two cumulative control voltages, one of said impedance devices being connected between said starting connections and running connections respectively as to furnish one of said control voltages in accordance with the voltage differential of said respective connections, said other impedance device being 30 connected in said motor circuit to furnish said other control voltage in dependence upon the current flowing in said motor circuit when the latter is connected to said starting connections, and auxiliary relay means connected between said 35 starting and running connections respectively and rated to perform responsive action when said voltage differential drops below a given magnitude, said relay means being connected to said tube so as to put said tube in operative condition only upon occurrence of said responsive action, and said two impedance devices being interconnected and rated so as to thereafter cause said tube to energize said relay to effect switching of said motor circuit only when said 40 voltage differential drops below a predetermined value lower than said magnitude while said current is below a given load magnitude.
